PIPE CLEANING TOOL

Varney S. Harlin, Oklahoma City, Okla.

Application October 3, 1949, Serial No. 119,342

3 Claims. (Cl. 166—18)

1

The device of the present invention relates to the operation of oil and gas wells, and more particularly to the production of oil and gas from such wells.

In producing oil and gas from cased wells, it is common practice to lower a string of production tubing into the well casing to reach the producing stratum, so that the well fluid may flow upwardly to the earth's surface through such string. In order to utilize the natural fluid pressure in the well as a boosting agent for the production fluid, it is common practice to provide the tubing string with a resilient packer for sealing the annulus between the string and the well casing. Such packers are located at a vertical point above the production stratum, and in order to function efficiently, they must have a perfect seal with the inside surface of the well casing.

In many instances, well packers fail to operate efficiently because of extraneous matter or deposit which has adhered to the casing surface.

The prime object of the present invention is to provide a casing cleaning tool or scraper which may be mounted on the tubing string subjacent the packer, and which will act to scrape the casing clean ahead of the packer, as the string is being lowered therein.

A further object is to provide a tool of this class which has no moving parts to become worn or to get out of order.

Another object is to provide a tool which will not hang or foul in the casing joints, as it is being lowered.

An additional object is to provide a tool which has a lower annular casing scraping edge, and which has vertically disposed ribs thereabove for breaking up deposited matter which has been scraped from the casing by said lower edge.

Another object is to provide a tool of this class which is simple to install.

Other objects will be apparent from the following description when taken in conjunction with the accompanying single sheet of drawings, wherein:

Figure 1 is an elevational view, partially in vertical section;

Figure 2 is a bottom view; and

Figures 3, 4 and 5 are horizontal sectional views taken substantially along the respective lines 3—3, 4—4, and 5—5 of Fig. 1.

Like characters of reference designate like parts in those figures of the drawings in which they occur.

In the drawings:

The reference numeral 1 indicates a fragment

2

of conventional well casing, and 2 indicates the lower portion of a section or sub of conventional production tubing, to the upper end of which a conventional well packer may be connected. The packer is not shown in the drawings.

The device of the present invention is adapted to be threadededly engaged with the lower end of the tubing section 2, so that it may be forced downwardly through the casing 1 when the tubing string is lowered therein.

The device of the present invention, per se, consists substantially of a tubate body 10 having an axial extending central core section 21, with the upper end of its bore tapered and threaded to connect the lower end of the tubing sub 2. Threads 11 are provided for this purpose. Directly below the threads 11, the core section 21 is slightly flared, and is provided with threads 12 into which another tubing section, not shown, may be engaged.

Below the threads 12, the bore of the body 10 is enlarged abruptly to form a depending skirt section 20, the upper end of which terminates in a downwardly facing shoulder 13. The lower end of the skirt section 20 terminates in an annular cutting edge 14 which is adapted to contact and scrape the wall of the casing 1. The lower edge 14 could be sharpened, if desired. The lower annular portion of the body 10 is im-

perforate to a point 15 somewhat above the edge 14. The periphery of the body 10 is provided with radially extending circumferentially spaced vertical ribs 16 which extend upwardly above the lower imperforate portion of the body, beginning at the above described point 15. The ribs 16 are formed by cutting circumferentially spaced substantially rectangular notches, slots, or longitudinal grooves 17 into the body wall. The slots 17 are co-extensive longitudinally with the ribs 16, and are machined to a sufficient depth laterally, that their lower end portions cause side openings in the lower enlarged portion of the bore of the body 10. These wall openings extend vertically from the point 15 upward to the internal shoulder 13, and are clearly shown in Fig. 4 where they are indicated by the reference numeral 18. The openings 18 form passages through which well fluid may pass outwardly from the enlarged lower portion of the bore of the body 10, and by which the fluid may enter the vertical slots 17 to travel upwardly above the body.

In operation, when the tubing string and the body 10 are being lowered into the well casing 1, the lower edge 14 acts to shear or scrape deposited

matter from the inside surface of the casing. The loosened deposit matter may find escape upwardly along the body through the slots or notches 17 by entering the slots 17 below the shoulder 13 and above the point 15.

It is pointed out that in some instances it is found that the well casing has partially collapsed below the earth's surface. In such cases, when an attempt is made to lower a packer in a conventional manner through the restriction, the packer lodges and is often damaged materially. When the present device is run into the casing ahead of the packer, it meets the restriction and halts downward movement of the tubing string. The entire tubing string is then withdrawn from the casing, and a conventional expander is then run into the casing to straighten out the restriction or deformity in the casing. The packer is therefore protected against damage by being wedged into the casing restriction.

Obviously the invention is susceptible to some change or alteration without defeating its practicability, and I therefore do not wish to be confined to the preferred embodiment shown in the drawings and described herein, further than I am limited by the scope of the appended claims.

I claim:

1. A deposit removing tool for use in well casing, and adapted to be run on a string of production tubing ahead of a well packer to form a continuation of the production channel of the string, including: an elongated tubular body which is open at both ends; a central core section of the body internally threaded to receive the adjacent ends of tubing string sections above and below the same; a lower depending annular skirt section of greater internal diameter than the external diameter of the core section; a circular cutting edge on the lower end of said skirt section; openings in the wall of said skirt section below said core section, and around the lower section of tubing, said openings providing a path for paraffin scraped from the well casing; and circumferentially spaced vertical slots in the exterior surface of said body and in communication with said wall openings to form a continuation of said path for paraffin.

2. A scraper for the casing of an oil well, including: an elongated tubular body open at both ends to form a continuation of the production

channel of a tubing string; an axially disposed central core section having threads in its upper end for attachment to the lower end of a tubing string section, and having threads in its lower end for attachment to the upper end of a tubing string section therebelow; an annular depending skirt below and of greater internal diameter than the external diameter of the core section, said skirt adapted to spacedly surround the lower string section concentrically; a circular paraffin cutting edge on the lower end of the skirt; lateral circumferentially spaced openings in the wall of said skirt below said core section and around the lower string section, said openings forming an escape path for paraffin scraped from the well casing; and circumferentially spaced slots in the exterior surface of said body and in communication with said openings to form a continuation of said escape path.

20 3. A production tubing attachment for scraping paraffin from an oil well casing, including: a tubate core section internally threaded to receive adjacent ends of axially aligned tubing sections extending above and below the same; a lower depending annular skirt portion, of greater internal diameter than the circumference of the lower tubing section, and spacedly surrounding the same concentrically; a circular paraffin cutting edge on the lower end of the skirt portion; circumferentially spaced openings through the wall of said skirt portion, said openings providing escape paths for paraffin scraped from the well casing by said cutting edge; and radially projecting circumferentially spaced vertical ribs formed in the periphery of the core section throughout its length, to provide vertical slots which form vertical continuations of said escape paths.

VARNEY S. HARLIN.
